Primary Examiner — Susan Bennett Hattan*Assistant Examiner* — Lauren D McVey(74) *Attorney, Agent, or Firm* — Muncy, Geissler, Olds & Lowe, P.C.(57) **CLAIM**

The ornamental design for a multi-functional grip, as shown and described.

DESCRIPTION

FIG. 1 is a front perspective view of a multi-functional grip according to the present invention.

FIG. 2 is a front view of the multi-functional grip of FIG. 1.

FIG. 3 is a rear view of the multi-functional grip of FIG. 1.

FIG. 4 is a left side view of the multi-functional grip of FIG. 1.

FIG. 5 is a right side view of the multi-functional grip of FIG. 1.

FIG. 6 is a top view of the multi-functional grip of FIG. 1; and,

FIG. 7 is a bottom view of the multi-functional grip of FIG. 1.

The broken lines immediately adjacent to the shaded areas depict the bounds of the claimed design and form no part of the claimed design, while all other broken lines are directed to environment. The broken lines form no part of the claimed design.
